UNITED STATES PATENT OFFICE.

WILLIAM M. YOUNG, OF LIBERTY, NEW YORK.

DESIGN FOR A BEARING-CONE AND DUST-CAP.

SPECIFICATION forming part of Design No. 34,012, dated January 29, 1901.

Application filed October 22, 1900. Serial No. 33,978. Term of patent 7 years.

To all whom it may concern:

Be it known that I, WILLIAM M. YOUNG, a citizen of the United States, and a resident of Liberty, in the county of Sullivan and State of New York, have invented and produced a new and original Design for a Bearing-Cone and Dust-Cap, of which the following is a specification, reference being had to the accompanying drawings forming a part thereof.

Figure 1 is a view in perspective, showing one side of the bearing-cone and dust-cap. Fig. 7 is a similar view showing the reverse side.

As shown in the drawings, the leading or material features of my design are an internally screw-threaded tubular-shaped part 3, having an exterior polygonal in cross-section

and terminated in a truncated cone at one end, as at 4, and cut off at right angles to the axis thereof at the opposite end, and a circular flange 5, extending around said portion 3 at right angles to the axis of said portion.

I claim as my invention—

The design for a bearing-cone and dust-cap substantially as shown and described.

Signed at New York, in the county of New York and State of New York, this 28th day of September, A. D. 1900.

WILLIAM M. YOUNG.
